DESIGN FOR A CIGAR BOX

Arthur Abraham Schwarz, New York, N. Y., assignor to Max Schwarz Manufacturer "La Primadona" Havana Cigars Ltd., New York, N. Y., a corporation of New York

Application January 11, 1939, Serial No. 82,298

Term of patent 14 years

To all whom it may concern:

Be it known that I, Arthur Abraham Schwarz, a citizen of the United States of America, residing in the city, county, and State of New York, have invented a new, original, and ornamental Design for a Cigar Box, of which the following is a specification, reference being had to the accompanying drawing, forming part thereof.

Fig. 1 is a front view of the cigar box showing my design, with the lid of the box in partly raised position.

Fig. 2 is a perspective view of the cigar box opened.

Fig. 3 is a perspective view of the cigar box closed.

I claim:

The ornamental design for a cigar box, as shown.

ARTHUR ABRAHAM SCHWARZ.
